J. J. COOPER.
END CONSTRUCTION FOR BOX CARS.
APPLICATION FILED MAY 28, 1915.

1,208,918.

Patented Dec. 19, 1916.

Inventor
James J. Cooper
A. H. Cornwall, Atty.

UNITED STATES PATENT OFFICE.

JAMES J. COOPER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

END CONSTRUCTION FOR BOX-CARS.

1,208,918.

Specification of Letters Patent. Patented Dec. 19, 1916.

Application filed May 28, 1915. Serial No. 30,955.

To all whom it may concern:

Be it known that I, JAMES J. COOPER, a citizen of the United States, residing at the city of St. Louis, State of Missouri, have 5 invented a certain new and useful Improvement in End Construction for Box-Cars, of which the following is a full, clear, and exact description, such as will enable others skilled in the art to which it appertains to 10 make and use the same, reference being had to the accompanying drawings, forming part of this specification.

This invention relates to certain improvements in sheet metal ends for box cars.

15 The object of the invention is to provide an improved form of end made up of corrugated sections of sheet metal, and containing features designed to provide an exceptionally secure attachment to the car superstructure.

20 A further object of the invention is the provision of an improved arrangement for securing car ends to the car superstructure.

Other objects of the invention will be obvious or pointed out hereinafter.

In the accompanying drawings, which illustrate one embodiment of the invention, Figure 1 shows a front elevation of one of the car ends; Fig. 2, a vertical section on line 2-2 of Fig. 1; Fig. 3, a horizontal section on line 3-3 of Fig. 1; Fig. 4, a detail taken at the corner of the car; Fig. 5, a detail showing a front view of a modified feature; Fig. 6, a detail illustrating a vertical section substantially on line 6-6 of Fig. 5. Fig. 7 is a partial elevation illustrating a modified form.

In the embodiment illustrated in these drawings, it will be seen that I provide an 40 end formed of three sections, 1, 2, and 3, although it is obvious that any desired number of sections may be used to form the end wall. In this form, the sections are connected on horizontal lines, the lower edges 45 of the upper sections being overlapped on the exterior of the upper edges of the subjacent sections. In each of the sections is an outwardly pressed corrugation 5 extending longitudinally of the section, preferably 50 highest at the median line of the section and gradually tapering back into the plane of the body portion of the section as it approaches the margins. At the ends of these corrugations, the metal of the sections is

pressed out to form inwardly opening pockets 6 having the walls 6^a toward the margins of the sections lying at substantially right angles to the body plane of the sections, and the walls opposite thereto merging gradually back into the plane of the sections. The margins of the sections are flanged rearwardly from the body plane thereof to provide the attaching flanges 7.

When the end is applied to the car superstructure, the marginal flanges 7 are placed to embrace the corner posts 8 and anchor plates 9 are affixed to the inner walls of the car with ends projecting beyond the corner posts, said plates extending rearwardly from the end of the car as far as desired and being bolted to the transom posts or other framing members of the car superstructure. The projecting ends of the anchor plates are adapted to project within the pockets 6, resting against the walls 6^a thereof, to 75 which walls the said ends are suitably secured. Compression plates 10 may then be placed in position to cover the reentrant sides of the corrugations 5 and pockets 6, being attached to the sections at both sides 80 of the corrugations by lines of fastenings 13, and secured at their ends to the anchor members 9 and corner posts 8. These compression plates are disposed approximately in the body plane of the sections, and beside closing the corrugations and pockets, 85 constitute compression members which co-operate with the corrugations 5 to form beams extending longitudinally of the sections, said beams being securely affixed to 90 the car superstructure at their ends by the anchor plates 9. Anchor plates 11 similar to anchor plates 9, may be applied to the exterior car walls and bolted through flanges 7 and the walls and frame members to the 95 anchor plates 9, as illustrated in Fig. 3.

In Figs. 5 and 6, I have illustrated a modified arrangement in which the walls 6^b of the pockets 6 taper obliquely back into the plane of the sections. A diagonally disposed 100 anchor plate 12 may have its end secured in a pocket of this conformation, said anchor plate extending back obliquely to one of the upper or lower longitudinal framing members of the car superstructure. This construction provides an exceptionally sturdy 105 end by virtue of the stiffness imparted by the beams extending longitudinally of the sec-

tions, and the secure attachment of the sections to the car superstructure at the ends of these beams.

In Fig. 7 I have illustrated a second modification in which, instead of forming the separate pockets 6 at the termini of the horizontal corrugations, I provide a continuous offset portion 6' extending across the entire width of the sections, and extending continuously from top to bottom of the end when said sections are joined. This offset is of substantially the same cross sectional form as that illustrated in Figs. 3 and 4, and tapers back into the plane of the upper and lower sections. This offset portion in addition to affording a securing place for the anchor strips 9 in the fashion illustrated in Figs. 3 and 4, or the strips 12, as illustrated in Figs. 5 and 6, provides in effect an auxiliary corner post, acting as a continuous strengthening member from top to bottom of the end structure, operating to stiffen the end and act as a load-carrying member adjacent the corners of the car.

I am aware that the device is capable of various modifications and changes not herein specifically illustrated and described, without departing from the spirit and scope of the invention.

What I claim is:

1. In a car structure, an end sheet extending transversely between the side walls and having outwardly pressed pockets formed therein adjacent its lateral extremities, and anchor plates secured to the sides of the car and having their outer ends secured in said pockets.

2. In a car frame members, an end sheet extending between said frame members and having portions adapted for attachment thereto, said sheet having integrally formed pockets adjacent the frame members and removed from its edges, and anchor plates secured to frame members and within said pockets on the interior of the car.

3. In a car, an end sheet extending transversely between the side walls and adapted for attachment to the corner posts, said sheet having a portion apart from the margin thereof disposed transversely of the major plane of the sheet, and securing means attached to a side wall portion and to said transversely directed portion of the sheet.

4. In a car, an end sheet extending transversely of the car and having a marginal flange directed substantially at right angles to the major plane of the sheet, said sheet having a transversely directed portion extending substantially at right angles from the major plane of the sheet and spaced apart from said marginal flange, and attaching members secured to the car wall and to said marginal flange and said transversely directed portion.

5. In a car, a sheet forming a wall portion

of the car, said sheet being shaped to provide a pocket spaced apart from its margin, said pocket having a wall extending at an angle from the major plane of the sheet, and an anchor member secured to said pocket wall and to a portion of the car body.

6. In a car, an end sheet having its lateral margins attached to car wall portions, said sheet being provided with a horizontally disposed corrugation, said sheet having deflected portions at the extremities of said corrugation extending at an angle from the major plane of the sheet, said deflected portions being spaced apart from the lateral margins of the sheet, means for securing the lateral marginal portions of the sheet to wall portions of the car, anchor members secured to said deflected portions and to car wall portions, and a tie plate covering the reentrant side of said corrugation and affixed to the end sheet at the sides of said corrugation, said tie plate being affixed at its extremities to the anchor members.

7. In a car, an end sheet having its lateral margins attached to side wall portions, anchor members secured to side wall portions and affixed to said sheet at points spaced apart inwardly from said margins, and a tie strip having its extremities connected to said anchor members and connected to said end sheet intermediate its extremities.

8. In a car, a wall sheet having attaching pockets with lateral walls formed adjacent opposite margins, a stiffening corrugation formed as a continuation of said attaching pockets, and attaching members seated in said pockets and secured to the lateral walls thereof.

9. In a car end, a wall sheet formed with attaching pockets adjacent opposite margins and with a stiffening corrugation extending intermediate said pockets, and a plate affixed to the inner side of said wall sheet and covering the reentrant sides of said pockets and said corrugation.

10. In a car end, a wall sheet formed with attaching pockets adjacent opposite margins and with a stiffening corrugation extending intermediate said pockets, attaching members affixed to said wall sheet in said pockets, and a plate affixed at its extremities to said attaching members and intermediate its extremities to said wall sheet in position to cover the reentrant sides of said corrugation and said pockets.

11. A car end composed of a plurality of sections horizontally disposed and secured together along their meeting margins, the lateral portions of said sections being secured to car wall portions, and anchor members secured to longitudinally deflected portions of the respective sections at points inset from their lateral margins and in position for attachment to car wall portions.

12. In a car, an end sheet extending be-

tween the corner posts and having portions adapted for attachment thereto, and anchor members secured to side portions of the car and having ends extending beyond the corner posts, said extending ends being riveted to the sheet at the inner side thereof.

13. In a car, an end sheet extending between the corner posts, and an anchor member secured to a side portion of the car and extending beyond the corner post, said an-

chor member being secured to the end sheet inside thereof at a point beyond the plane of the end wall.

In testimony whereof I hereunto affix my signature in the presence of two witnesses, 15 this 17th day of May, 1915.

JAMES J. COOPER.
